UNITED STATES PATENT OFFICE.

WALTER S. ADAMS, OF PHILADELPHIA, PENNSYLVANIA, ASSIGNOR TO
JOHN A. BRILL, OF SAME PLACE.

DESIGN FOR A TRUCK SIDE BAR.

SPECIFICATION forming part of Design No. 25,102, dated January 28, 1896.

Application filed November 16, 1893. Serial No. 491,156. Term of patent 14 years.

To all whom it may concern:

Be it known that I, WALTER S. ADAMS, a citizen of the United States, residing at Philadelphia, in the county of Philadelphia and State of Pennsylvania, have invented and produced a new and original Design for Truck Side Bars, of which the following is a specification, reference being had to the accompanying drawings, forming part thereof.

10 My invention relates to a design for a truck side bar for cars, and the leading feature consists in the configuration and outline of the side bar, as more fully hereinafter set forth.

In the drawings, Figure 1 is a side elevation of the side bar; Fig. 2, a plan view; Fig. 3, an end view; Fig. 4, a cross-section on the line *y y* in Fig. 1, and Fig. 5 a cross-section on the line *x x* in Fig. 1.

The side bar is formed essentially of central bars 1 united at the ends to axle-box yokes 2 having the outline of an inverted **U**. The yokes 2 extend above and below the plane of the bar 1, the tops of the yokes 2 having a curved outline, their lower outer sides being 25 also curved. 3 are bifurcated arms extending from the sides of the yokes 2 on the same plane as the bar 1, said arms at their ends

having plates 4 with ribs 5 at their edges. From below the plates 4 extend ears 4^a. At the under side of the portion 6 of the yokes 2 are side projections 7 that lie above the opening of said yoke. At the junction of the bar 1 with the yokes 2 and on the upper side of said bar are circular dish-shaped plates 8, and through said plates 8 and the bar 1 pass 35 holes 9. At the junction of the yoke 2 with the arms 3 are also located dish-shaped plates 10, and through said plates and the arms 3 are holes 11.

It will be seen that the dish-shaped plates 40 8, 8, and 10 are wider than the yokes 2, and that the plates 4 are wider than the plates 8 10, and the bar 1 has plane sides up to the yokes.

I claim—

45 The design for a truck side bar, substantially as herein shown and described.

Signed at Philadelphia, in the county of Philadelphia and State of Pennsylvania, this 30th day of October, 1893.

WALTER S. ADAMS.
